UNITED STATES PATENT OFFICE.

CLARA H. HAVEMEYER, OF SPRINGFIELD, MASSACHUSETTS, ASSIGNOR TO PACKAGE PAPER AND SUPPLY CORPORATION, A CORPORATION OF MASSACHUSETTS.

DESIGN FOR AN ORNAMENTAL PAPER.

61,040.

Specification for Design.

Patented June 6, 1922.

Application filed October 19, 1921. Serial No. 508,877. Term of patent 3½ years.

To all whom it may concern:

Be it known that I, CLARA H. HAVEMEYER, a citizen of the United States, residing at Springfield, in the county of Hampden and State of Massachusetts, have invented a new, original, and ornamental Design for an Ornamental Paper, of which the following is a specification, reference being had to the accompanying drawing, forming a part thereof.

The figure is a view showing my new design.

I claim:

The ornamental design for an ornamental paper, as shown.

CLARA H. HAVEMEYER.
